(57) **CLAIM**

The ornamental design for a foam noodle building block, as shown and described.

DESCRIPTION

FIG. 1 is a perspective view of a 1st embodiment of a foam noodle building block showing our new design;

FIG. 2 is a top view thereof, the bottom being a mirror image of the top;

FIG. 3 is a right side view thereof, the left side being a mirror image of the right side;

FIG. 4 is front end view thereof; the back end being a mirror image of the front end; and,

FIG. 5 is a perspective of a 2nd embodiment of a foam noodle building block having a shorter length.
